UNITED STATES PATENT OFFICE.

SAMUEL C. McKEOWN, OF EAST ORANGE, NEW JERSEY, ASSIGNOR TO SPLITDORF ELECTRICAL COMPANY, OF NEWARK, NEW JERSEY.

CIRCUIT-BREAKER MECHANISM.

Application filed March 3, 1919. Serial No. 280,448.

To all whom it may concern:

Be it known that I, SAMUEL C. McKEOWN, a citizen of the United States, residing at East Orange, in the county of Essex and 5 State of New Jersey, have invented certain new and useful Improvements in a Circuit-Breaker Mechanism, of which the following is a specification.

My invention relates particularly to circuit breakers used in connection with ignition generators wherein it is essential to vary the timing of the spark produced by the generator to conform with the speed of the engine on which the ignition generator is 10 placed. In certain types of ignition generators the entire pole structure is rotatable through a certain angle to accomplish the timing of the spark. In other types of ignition generators the breaker box carrying 15 cams which cooperate with the rotating part of the circuit breaker, is adjustable through certain angles for spark timing purposes. Where the breaker members are relatively stationary and the operating cam rotates, 20 considerable difficulty is encountered in constructing a breaker box which carries the breaker members so that it may be readily moved about the operating cam the required number of degrees for timing purposes. 25 Where the breaker members are moved with the breaker box a flexible or sliding connection is required at the point where the primary of the induction coil is brought out to the stationary contact. 30

It is the object of my invention to provide a circuit breaker mechanism in which the circuit breaker members are relatively stationary and in which there is no moving or 35 sliding connection between the primary wire and the stationary contact.

While attaining the general object of my invention it is a further object to provide a construction that is easy and cheap to manufacture and one that is not apt to get out 40 of order in practice.

Other and further objects will be apparent to one skilled in the art after a study of the specification taken in connection with the drawing, in which—

Figure 1 is an end view of a portion of 50 an ignition generator showing the breaker mechanism in position.

Figure 2 is a side elevation of my breaker mechanism with the breaker box cover 55 broken away to show the interior parts.

Figure 3 is an end view similar to Figure 1 but with certain parts removed.

Figure 4 is a perspective view of that part of the breaker mechanism which has been removed to show the parts of Figure 3.

Referring now to the details wherein like numbers refer to corresponding parts in the various views, 1 is the end plate of an ignition generator on the operating shaft of which a cam 2 is mounted, being held in place by the usual taper on the shaft and a screw 3 adapted to engage a threaded hole in the end of the shaft. Mounted on the plate 1 but insulated therefrom is a plate 4 carrying an adjustable contact 5. Connected to the plate 4 is one end of the primary winding 6, the other end of the primary winding being grounded to the framework of the generator in the well known manner. A movable member 7 carrying a contact 8 is mounted so that the contact 8 cooperates with the contact 5 in the usual manner. One end 9 of the movable member 7 extends in an arcuate form substantially parallel to the outer periphery of the cam 2. A controlling spring 10 is fastened to a part of the plate 1 in any suitable manner such as screw 11 which enters the boss 12. A boss 13 is provided on the other side of the shaft so that the spring 10 may be mounted thereon for the opposite direction of rotation, it being understood that the breaker parts are also designed so as to be turned over for opposite direction of rotation. A plate 14 having holes 15 is fastened 90 to the plate 1 by screws 31. The plate 14 supports a carrier member 16 by means of a suitable stud 17 coaxial with the axis of the cam and which passes through the member 16 and has the end swedged over. Two 95 parallel arms 18 extend from one face of the member 16 and between these arms is loosely positioned a roller member having a fiber body 19 with preferably metal ends 20. The arms 18 are so formed that the roller 19 may be readily dropped through from one side but it will not pass between the arms on the other side so when the plate 14 is in the position shown in Figure 1 the roller 19 is held in the position shown more clearly in 105 Figures 3 and 4, in the latter of which the roller is removed from the carrier and is shown in its operative position. The metal end 20 is adapted to abut against the fiber plate 21 which for this purpose is extended 110

beyond the plate 4 so as to produce the least amount of friction and thus allowing the roller 19 to turn readily between the arms 18 as the roller is engaged by the noses of the 5 cam 2. The carrier 16 also has a lug 22 which for one direction of rotation operates in the segmental recess 23 in plate 14 and for the other direction of rotation is adapted to operate in the cutway portion 24 thereby 10 serving as a stop for the carrier member 16 and the operating lever 25 that is connected to the stud 17 by any suitable means such as a screw 26. The lever 25 is held in position by means of a screw 26 passing through 15 the lever and a breaker box cover 27 into the enlarged end of the stud 17, which enlarged end is on the opposite side of the plate 14, from the end of the stud shown in Figure 4. A spring washer 28 as shown in Figure 2 20 provides a frictional contact between the cover 27 and the lever 25.

From the above description it will be readily seen that since the outer circumference of the cam, the arm 9 and the path of 25 movement of the roller 19 are all concentric, the operation of the handle 25 to move the carrier 16 shifts the position of the roller 19 circumferentially about the lobe of the cam 2 so as to vary the time of operation of the 30 movable breaker member 7. For example, if the direction of the rotation of the cam 2 be clockwise, Fig. 3, and the roller be shifted clockwise, the push transmitted to the arm 9 by the roller 19 will occur at a later angle 35 in the rotation of the cam, thus retarding the spark, that is to say, the time of opening of the circuit breaker contacts. In order to stop the engine it is usual to ground the insulated end of the primary 6 and for this 40 purpose I have provided a contact stud 29 insulated from the cover 27 and having a spring connection 30 with the plate 4 thereby allowing the grounding stud to be connected to the stud 29 in the usual manner.

45 It will be understood that various changes and alterations may be made in the details without departing from the spirit of my invention and the scope of the appended claims.

50 Having thus described my invention, what I claim is:—

1. In a circuit breaker mechanism, the combination of a stationary member carrying a contact, a movable member carrying a cooperating contact, a cam, and an intermediate adjustable member adapted to be 55 acted on by the cam for operating the movable member.

60 2. In a circuit breaker mechanism, the combination of a stationary member carrying a contact, a movable member carrying a cooperating contact, a cam, a member loosely positioned between one end of the movable member and the cam and adapted to be 65 acted on by the cam for operating the mov-

able member and means for adjusting the location of the loosely positioned member for the purpose described.

3. In a circuit breaker mechanism, the combination of a stationary member carrying a contact, a movable member carrying a cooperating contact, a cam, an intermediate member positioned between one end of the movable member and the cam and adapted to be acted on by the cam for operating 70 the movable member, a carrier for the intermediate member and means for shifting the carrier to vary the time when the cam engages the intermediate member.

4. In a circuit breaker mechanism, the combination of a stationary member carrying a contact, a movable member carrying a cooperating contact, a cam, an intermediate member positioned between one end of the movable member and the cam and adapted 75 to be acted on by the cam for operating the movable member, a carrier having arms between which said intermediate member is carried and a lever operatively attached to the carrier for shifting the position of the 80 carrier and intermediate member with respect to the cam.

5. In a circuit breaker mechanism, the combination of a stationary member carrying a contact, a movable member carrying a 85 cooperating contact, a cam, a roller between the cam and one end of the movable member, a carrier to guide and support the roller and means for moving the carrier at will.

6. In a circuit breaker mechanism, the combination of a stationary member carrying a contact, a movable member carrying a cooperating contact, a cam, a roller between the cam and one end of the movable member, a plate with stop notches therein, 105 a carrier supported by the plate and having arms to support said roller and a stop lug positioned within one of the notches on said plate and a lever for moving the carrier within the limits imposed by said last mentioned notch and stop lug.

7. In a circuit breaker mechanism, the combination of a stationary member carrying a contact, a movable member carrying a cooperating contact, a cam, and an independently movable member positioned adjacent the first mentioned movable member and in the path of movement of said cam whereby the action of said cam is transmitted through the independently movable 120 member to the movable member carrying said contact and means for adjusting the independently movable member relative to the first mentioned movable member for changing the time of separation of said contacts.

8. In a circuit breaker mechanism, the combination of a generator end plate, a fiber plate carried thereon, a stationary member fastened to the end plate but insulated therefrom and carrying an adjustable contact, a 125 130

movable member carried on the end plate and having a contact to cooperate with the first contact, a cam, a second plate fastened to the end plate, a carrier movably supported on the second plate and having two arms extending in the same direction, a roller loosely supported between said arms and having one end resting against said fiber plate, said roller being positioned between

the cam and one end of the movable member 10 and adapted to operate the latter when acted on by the cam, a cover for all of said mechanism and a lever outside the cover having connecting means through the cover with the carrier to shift its position with respect to 15 said cam.

In witness whereof, I affix my signature.
SAMUEL C. McKEOWN.
